UNITED STATES PATENT OFFICE.

JAMES A. RIDDLE, OF HOTCHKISS, COLORADO.

NAIL-HOLDING HAMMER.

1,052,965.

Specification of Letters Patent. Patented Feb. 11, 1913.

Application filed August 15, 1910. Serial No. 577,164.

To all whom it may concern:

Be it known that I, JAMES A. RIDDLE, a citizen of the United States, residing at Hotchkiss, in the county of Delta, State of Colorado, have invented certain new and useful Improvements in Nail-Holding Hammers; and I do hereby declare the following to be a full, clear, and exact description of the invention, such as will enable others skilled in the art to which it appertains to make and use the same.

This invention relates to hammers adapted to hold a nail upon its head so that it may be given its first driving stroke into the wood.

The object of the present invention is to equip a claw hammer with a catch that will coöperate with the claws in more effectively holding a nail for driving than usual, and will release the nail after the initial driving stroke more readily than usual.

In the accompanying drawing forming part of this specification:—Figure 1 is a side elevation of a claw hammer constructed in accordance with my invention. Fig. 2 is a cross sectional view taken on the line 2—2, Fig. 1. Fig. 3 is a cross sectional view taken on the line 3—3, Fig. 2.

Referring now to the drawing, the numeral 10 designates in general a claw hammer head comprising a handle receiving eye or socket 11, from one side of which projects a pole 12, and from the opposite side of which project claws 13, a handle 14 being fitted in the handle socket, these parts all being of the usual and well-known construction.

Arranged upon the socket 11 is a rib 15, this rib being approximately wedge shaped in cross section and having its flat face 16 underlying and arranged approximately in parallelism with the bases 17 of the claws, and having its inclined face 18 merging with the edge of the socket 11, and further having its end faces 19 flush with the sides of the socket. The flat face of the rib is made

slightly concave so as to effectively hold a nail head.

In mounting the nail for driving the head of the nail is brought to bear against the end 50 face of the handle socket with the edge of the nail head bearing against the slightly concave face of the rib, the shank of the nail is then pressed back between the claws of the hammer and wedged in the fork thereof. 55 The hammer is then turned with the point of the nail in the direction of the wood or material into which the nail is to be started, when the initial or starting stroke is made 60 the shank of the nail is automatically released from the grip of the claws. When the head of the nail will slip without resistance from the face of the handle socket and opposing face of the rib leaving the nail started and in position for driving in the 65 ordinary way. This is an advantage over devices of this character hitherto constructed and which have dove-tailed slots engaging the nail head, in that a greater number and variety of nails may be started and 70 driven in a given period of time than in ordinary devices, by virtue of the increased quickness with which the nail can be placed in position in the hammer for driving and the automatic disengaging of the nail from 75 the hammer as the initial stroke is made.

What is claimed is:—

The combination with a hammer head having claws and a handle receiving socket portion, of a wedge-shaped rib on the socket 80 portion at the entrance thereof and projecting forward and extending beneath the claws the inner face of the wedge-shaped rib being concaved to receive a nail head the shank of which nail is adapted to project be- 85 tween the claws of the head.

In testimony whereof, I affix my signature, in presence of two witnesses.

JAMES A. RIDDLE.
